DESIGN FOR A CONFECTIONARY PRODUCT

Henry J. Willems, Kenosha, Wis.

Application October 22, 1943, Serial No. 111,451

Term of patent 14 years

To all whom it may concern:

Be it known that I, Henry J. Willems, a citizen of the United States, residing at Kenosha, in the county of Kenosha and State of Wisconsin, have invented a new, original, and ornamental Design for Confectionary Product, of which the following is a specification, reference being had to the accompanying drawing, forming part thereof.

The single figure is a perspective view of a confectionary product showing my new design.

The essential features of the design reside in the portion shown in full lines.

I claim:

The ornamental design for a confectionary product, as shown and described.

HENRY J. WILLEMS.
